UNITED STATES PATENT OFFICE

JAMES J. SANTIAGO, OF LOS ANGELES, CALIFORNIA, ASSIGNOR TO JOHN GRANT, OF LOS ANGELES, CALIFORNIA

SWINGING CUTTER EXPANDING REAMER

Application filed November 13, 1928. Serial No. 319,080.

This invention has to do with expanding well reamers or underreamers, and more particularly with expanding underreamers for rotary drilling. It may be stated as one of the general objects of the invention to provide a reamer construction capable of relatively large expansion in diameter. There are other objects of the invention, such as will appear from a consideration of the following detailed description but needing no preliminary mention.

The present invention is characterized by the utilization of cutters or cutter elements which swing in a vertical plane for expansion and contraction. Cutters which swing in a horizontal plane have been heretofore proposed for rotary underreamers; and cutters that move upwardly and outwardly for expansion have been in use. The present invention provides cutters that move upwardly and outwardly, but in which the cutter expanding movement is a swinging movement, either for one or both ends of a cutter, about a horizontal pivot center. The cutter or cutter element provided by this invention is one which has preferably a considerable longitudinal extent. The cutter as a whole does not swing about a single horizontal pivotal center; but, as will hereinafter be described in preferred and illustrative detail, either one end, and preferably the upper end, of the cutter swings about such a horizontal pivotal center—swings in a curved path in a vertical plane—or both ends, and therefore all points on the cutter, swing in circular or curved paths in a vertical plane.

For the purpose of describing in full detail a typical embodiment of the invention, and so that those skilled in the art may comprehend the invention itself by way of an understanding of the details of a preferred and illustrative structure, I illustrate such structures in the accompanying drawings, in which

Figure 1 is a side elevation of one form of underreamer in accordance with my invention.

Fig. 2 is a longitudinal vertical central section taken on line 2—2 of Figure 1, both Figures 1 and 2 showing the reamer in its expanded condition.

Fig. 3 is a view similar to Figure 2 but showing the reamer in contracted position.

Fig. 4 is a cross section on line 4—4 of Figure 2.

Fig. 5 is a cross section on line 5—5 of Figure 2.

Fig. 6 is a view similar to Figure 1, but showing a modified form.

Fig. 7 is a longitudinal central section on line 7—7 of Figure 6.

Fig. 8 is a cross section on line 8—8 of Figure 7.

Fig. 9 is a cross section on line 9—9 of Figure 7, and

Fig. 10 is a section similar to that of Figure 7 but showing the reamer in contracted condition.

In the drawings, a suitable reamer body is illustrated at 10 adapted at its upper end at 11, for connection with a drill stem, and at its lower end, at 12, for connection with the drilling bit 13 that is usually run below a reamer or underreamer in rotary work. As shown in the specific design of these drawings, the body 10 is slotted as at 14 to accommodate the cutters; and the longitudinal watercourse 15 is carried vertically across the slotted portion of the body by a water tube 16, to deliver circulating fluid from the drill stem above to the circulation passages in the drill bit 13 below.

I have preferred to illustrate here that form of cutter which is known as a rock cutter, or a cutter involving a cutting roller. Any other form of cutter may, however, be used. Thus, as shown in the various views, the cutter may be regarded as being composed of two parts, specifically the part 20 which may be called a cutter carrier, and the part 21, the roller, which may be called the cutting element. In the specific form here shown, the cutter carrier is in the form of a stem or mandrel upon which the cutting element, the roller 21, has a rotative bearing; but broadly the cutter carrier may have a cutting element of any character on it or carried by it.

As shown in Figures 1 to 5, the lower end of each cutter carrier 20 is pivotally mounted at 22 on the upper end of a spring supported

rod or plunger 23, each rod 23 being constantly urged upward by a spring 24 located in a spring recess 25 in the body.

- The upper ends of cutter carriers 20 are 5 pivotally connected, at 26, with the swinging ends of pivoted links or arms 27, pivoted on horizontal axes, at 28, to the body. These pivoted swinging arms 27 thus swing in vertical planes, and they may swing between 10 the outwardly extended or expanded positions shown in Figure 2 and the downwardly extending or contracted positions shown in Figure 3. In the contracted positions the arms 27 preferably are stopped before they 15 quite reach a vertical position, as in the typical position shown in Figure 3, by the stop surfaces 30, as shown in Figure 3. Thus the upward pressure of springs 24 tends at all times to start the arms 27 in their outward 20 and upward swinging movements, toward the positions of Figure 2, and the arrangement insures expansion of the cutters when they pass out of the casing and into the drill hole below. Once the cutters are passed out of 25 the casing, the spring action, tending at all times to press the cutters up, presses them out and up toward the position of Figure 2; and the relative upward drag of the formation on the cutters also tends to move them 30 upwardly, and therefore outwardly, to the expanded positions. In order to collapse or contract the cutters it is only necessary to pull them up so that the swinging arms 27 contact with the lower end of the casing, or 35 with the casing shoe, when the arms, and the cutters, are pressed downwardly and inwardly to the collapsed position.

In Figures 6 to 10 the structure illustrated is somewhat similar to that shown in Figures 40 1 to 5, but here I show a cutter carrier 20a which is integral with the rolling cutter 21a. Instead of the cutter 21a rotating on the carrier as a non-rotating shaft or pin, the carrier 20a here rotates with the cutter, and 45 the upper and lower ends of the carrier are mounted in pivot blocks 20b which have trunnion mountings 20c in the pairs of vertically swinging arms 27a. These pairs of vertically swinging arms 27a are provided at both 50 the upper and lower ends of the carriers, and springs 24a tend to rotate the arms 27a outwardly and upwardly to move the cutters to their outward expanded positions. The springs are here shown applied to the upper 55 arms 27a, but they may be applied as well to the lower arms, or to both. The relative movements will be readily understood from a consideration of Figures 7 and 10. In this form of device, where the springs 24a act 60 directly to rotate the swinging arms 27a, instead of acting upwardly on the cutter carriers, it is immaterial how far the cutters and cutter carriers, and the arms, swing inwardly to reach the collapsed position, and therefore 65 no stops to the inward swinging motions are

essential. The swinging arms at each end of each cutter carrier are preferably provided in pairs, as will readily be seen from an inspection of Figures 8 and 9, and the pairs at the lower ends of the cutter carriers, as shown in Figure 9, are spaced widely enough apart to receive between them the lower ends of the cutters when the parts are in their contracted positions as shown in Figure 10.

Although I show the respective upper and lower arms 27a as being of equal lengths, and therefore show the cutters and cutter carriers swinging in a movement which keeps each cutter or cutter carrier parallel to itself at all times; it will readily be understood that the ends of the arms 27a may be made unequal to any desired extent, so that either the upper or the lower end of each cutter may swing outwardly more or less than the other end.

It is preferred, in either of the forms here illustrated, to make the swinging arms 27 or 27a fit the body slots 14 laterally so that the cutter-carrying arms are thus made to bear laterally against the side walls of the body slot, thus to be supported as strongly as possible against rotary or tangential forces exerted upon the cutters and therefore upon the cutter carriers and arms. Within the limits of good design, and particularly within the limits of strength of the arms 27 or 27a, it will be apparent that a reamer constructed as herein described can be made to expand by any amount desired; the amount of expansion being only limited by the lengths of the swinging arms.

In the form of Figures 1 to 5, where the lower ends of the cutters are supported upon the vertically moving spring rods 23, strength at the lower ends against inward forces may be attained by having the head blocks 23a of the spring bars 23 bear inwardly against the abutment faces 23b of the body as shown in Figures 2 and 3. And strength at the lower ends of the cutters, against rotative or tangential forces applied to the cutters, is attained by having the heads 23a confined laterally between the side walls 14a of the body slot 14, which may be narrowed for that purpose at its lower end, as is clearly shown in Figure 1.

I claim:

1. An expanding reamer comprising a body adapted to be attached to a drill stem, a cutter-carrying arm mounted to swing on a horizontal pivot on the body, a cutter pivotally mounted on the swinging end of said arm, and actuating means carried by the body tending to swing the arm on its horizontal pivot.

2. An expanding reamer comprising a body adapted to be attached to a drill stem, a cutter-carrying arm mounted to swing on a horizontal pivot on the body, said arm being restricted in its swinging movement between a position extending downwardly from its

pivot and a position extending outwardly from its pivot, a cutter pivotally mounted on the swinging end of said arm, and actuating means carried by the body tending to swing the arm outwardly.

3. An expanding reamer comprising a body adapted to be attached to a drill stem, a cutter-carrying arm mounted to swing on a horizontal pivot on the body, a cutter pivotally mounted at one end on the swinging end of said arm, movable mounting means in the body for the other end of the cutter, and actuating means carried by the body tending to swing said arm about its pivot.

4. An expanding reamer, comprising a body having a vertically extending slot, a vertically swinging cutter-supporting arm mounted at one end on a horizontal axis in the body slot, said arm being restricted to movement substantially between a position extending downwardly from its pivot and a position extending outwardly from its pivot, and said arm bearing laterally against the wall of the body slot, a cutter pivotally connected to the swinging end of said arm, and actuating means carried by the body tending to move the cutter and arm outwardly.

5. An expanding reamer, comprising a body having a vertically extending slot, a vertically swinging cutter-supporting arm mounted at one end on a horizontal axis in the body slot, said arm being restricted to movement substantially between a position extending downwardly from its pivot and a position extending outwardly from its pivot, and said arm bearing laterally against the wall of the body slot, a cutter pivotally connected at its upper end to the swinging end of said arm, movable mounting means in the body for the lower end of said cutter, and actuating means carried by the body tending to move the cutter and arm outwardly.

6. An expanding reamer, comprising a body having a vertical cutter receiving slot, upper and lower cutter-supporting arms mounted at one end on horizontal pivots in the body slot so as to swing in a vertical plane, a cutter pivotally mounted on the swinging ends of said two arms, said arms bearing laterally against the side walls of the body slot, and actuating means carried by the body tending to swing said arms upwardly and outwardly about their horizontal pivots.

7. An expanding reamer, comprising a body, upper and lower cutter carrying arms pivoted at one end on a horizontal axis on the body so as to swing in a vertical plane, a cutter pivotally mounted at its upper and lower ends, respectively, on the swinging ends of the two swinging arms, and actuating means carried by the body tending to swing said arms upwardly and outwardly with respect to the body.

8. An underreaming tool comprising an elongated body portion adapted to be low-

ered through a well casing, a plurality of cylindrical cutters mounted on said body and arranged therearound in position to perform an underreaming operation, said cutters being mounted upon shafts which extend lengthwise of said body, said shafts being movable lengthwise of said body, normally pendant links pivotally connecting the upper ends of said shafts with said body, means to force said shafts upwardly and lengthwise of said body and thereby cause said links to force said shafts radially outward from said body, and means to stop the swing of said links at an upward inclination relative to their inner pivots.

9. An underreaming tool comprising an elongated body portion adapted to be lowered through a well casing, a cutter shaft mounted by the side of said body, a cutter mounted upon said shaft, a link pivotally connecting said shaft with said body, means to move said shaft lengthwise to cause said shaft and cutter to swing outwardly to the underreaming position, and stop means to arrest the outward swing of said link, the inner end of said link having a bearing surface which is curved concentrically with relation to its attaching pivot, and the aforementioned body of the tool having a correspondingly curved bearing surface to cooperate with and having a working fit upon said bearing surface of said link.

10. An underreaming tool comprising an elongated body portion adapted to be lowered through a well casing, a cutter shaft mounted on said body and extending lengthwise thereof, a cutter mounted upon said shaft in position to perform an underreaming operation, said shaft being movable lengthwise of said body, a link pivotally connecting the upper end of said shaft with said body, and means to force said shaft upwardly and lengthwise of said body and thereby cause said link to force said shaft radially outward from said body, said body being provided with a stop shoulder which arrests the swinging of said link after it reaches an upward inclination with relation to its inner pivot.

11. An underreaming tool comprising an elongated body portion adapted to be lowered through a well casing, a cylindrical cutter mounted adjacent said body and positioned to perform an underreaming operation, said cutter being mounted upon a shaft which extends lengthwise of said body, a link pivotally connecting said shaft with said body, and actuating means carried by the body acting to force said shaft lengthwise of said body and thereby cause said link to force said shaft radially outward from said body.

12. An underreaming tool comprising an elongated body portion adapted to be lowered through a well casing, a cylindrical cut-

ter mounted adjacent said body portion and positioned to perform an underreaming operation, said cutter being mounted upon a shaft which extends lengthwise of said body, a link pivotally connecting said shaft with said body, actuating means carried by the body acting to force said shaft lengthwise of said body and thereby cause said link to force said shaft radially outward from said body, and a follower against which said spring operates to move said shaft in the direction of its length as aforesaid.

In witness that I claim the foregoing I have hereunto subscribed my name this 30th day of October, 1928.

15 JAMES J. SANTIAGO.
